DRAFT-RIGGING FOR RAILWAY-CARS.

1,070,061.

Specification of Letters Patent. Patented Aug. 12, 1913.

Application filed March 31, 1913. Serial No. 757,856.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of cheap construction and efficient operation.

In the drawings forming a part of this specification Figure 1 is a side elevation partly in vertical longitudinal section on line 1—1 of Fig. 2 of a draft rigging embodying my invention, the parts thereof being in normal position. Fig. 2 is a plan view partly in horizontal section on line 2—2 of Fig. 1. Fig. 3 is a side elevation partly in vertical longitudinal section showing the position of the parts in full draft. Fig. 4 is a side elevation partly in longitudinal section showing the position of the parts in full buff.

Referring to the drawings 5, 5 represent draft members, or parts of the car frame to which the draft rigging is applied, 6 the end sill, 7 the buffer block, 8 the draw-bar carrying iron, 9 the tie plate, suitably secured to the draft members, 10, 10 front stop members, having stop shoulders 11, 11, 12, 12 rear stop members, having stop shoulders 13, 13, 14 the draw-bar, and 15 a draft yoke secured to the draw-bar, and having a lateral opening 16. Within the lateral opening of the yoke are mounted the front and rear followers 17 and 18 respectively, adapted to engage the stop members. Between said followers is disposed the friction mechanism 19 of the draft gear, and rearwardly of the rear follower 18 is mounted the spring mechanism 20 of the draft gear.

The friction mechanism 19 comprises a housing 21, a wedge 22 and friction blocks 23, 23. The housing 21 slidably engages within the yoke 15, and is adapted to reciprocate. The said housing is preferably a box-like member rectangular in shape, and has a longitudinal opening 24. Rearwardly

it is provided with oppositely arranged 55 upper and lower angular friction faces 25, 25.

The friction blocks 23, 23 are preferably two in number, each triangular in cross section, and preferably equilateral in cross section. The outer friction face 26 of each friction block is adapted to engage a friction face 25 of the housing 21. The inner friction face 27 of each friction block is adapted to engage a friction face 28 of the 60 wedge 22 hereinafter described. The rear friction face 29 of each friction block is adapted to engage the front face of the rear follower 18. The said housing is provided at either side with an outwardly extended 65 lug or ear 30, longitudinally perforated for the passage of a spring bolt 31 hereinafter described.

The wedge 22 is a block-like member having a forward face 32 adapted to engage the 75 rear face of the front follower 17, and is rearwardly provided with opposed rearwardly converging friction faces 28, 28. In preferable construction of the wedge 22 the same is provided with a transverse opening 80 33. The rear end of the wedge 22 has a flat face 34 adapted in the operation of the gear to limit the movement thereof by engagement with the front face of the rear follower 18.

The spring bolts 31 are preferably two in number, there being one at either side of the friction mechanism, each with a head 35 seated against the front face of the ear 30 of the housing. Each of said bolts extends 90 rearwardly from said ear through a perforation 36 in the follower, (there being one perforation for each bolt). Said bolts each terminate a suitable length rearwardly from the rear follower in a threaded portion bearing a nut 37. A saddle 38 is mounted between said bolts and back of the follower, said saddle comprising a transverse plate 39 with perforations 40 at either end for the passage of a spring bolt, and having forwardly extended legs 41, 41 engaging the rear face of the rear follower. Preferably, said legs are between the spring bolts, and engage the follower at either side of the yoke strap.

A spring seat 42 is mounted upon the spring bolts at their rear ends, and bears against the nuts 37, 37. The bolts 31 pass-

ing through perforations 43, 43 at either side of the spring seat. Between the spring seat 42 and the saddle 38 is mounted the spring mechanism 20. Said spring mechanism preferably consists of an outer spring 44 and an inner spring 45 nested therein.

In normal position of the parts of the draft rigging, as illustrated in Figs. 1 and 2 of the drawings, the followers engage the stop shoulders, and the friction blocks are substantially within the housing and adjacent each other. On rearward movement of the draw-bar the wedge is forced rearwardly by the front follower, the rear follower is stationary against the rear stop shoulders, and as the wedge 22 travels rearwardly within the housing 21 the friction blocks 23, 23 are forced upwardly and downwardly respectively, and away from each other, in sliding frictional action with the wedge, rear follower and housing. The engagement of the outer friction face 26 of each friction block with a friction face 25 of the housing forces the housing forwardly, the spring bolts are thereby drawn forwardly, pulling the spring seat 42 toward the rear follower 18, and compressing the spring mechanism 20 between the spring seat 42 and the saddle 38, which is stationary against the rear follower. This action in buffering movement of the gear continues until the wedge's rear face 34 engages the rear follower, and the parts are in the position illustrated in Fig. 3 of the drawings. On pulling movement of the draw-bar the front follower 17 is stationary against the front stop shoulders, and the wedge 22 is stationary against said follower, the yoke 15 draws the rear follower 18 forwardly, thus forcing the friction blocks away from each other, the said friction blocks in their separating movement being in frictional engagement with the rear follower, the wedge and housing, and forcing the housing forwardly in its relation to the forwardly traveling rear follower. Meanwhile the spring mechanism is being compressed between the saddle 38 and the spring seat 42 by the traction of the spring bolts. On full compression in pulling movement of the gear the parts are in the position illustrated in Fig. 4 of the drawings.

I claim:

1. In a draft rigging for railway cars, in combination, a draw-bar, stop members, followers, a draft yoke, friction mechanism within the yoke, spring mechanism without the yoke, a saddle, a spring seat and spring bolts, the friction mechanism comprising a housing, a wedge and friction blocks operating in said housing, a spring mechanism being mounted between the saddle and the spring seat, the saddle engaging the rear follower, the spring seat being connected to the housing by the spring bolts, and the

friction blocks operating to forwardly compress the springs on both forward and rearward movement of the draw-bar.

2. In a device of the character described, a yoke, followers, friction mechanism within the yoke and spring mechanism without the yoke, the friction mechanism comprising a housing open at both ends, a wedge and friction blocks within said housing, the spring mechanism being seated independently of the yoke and against the rear follower, and operatively connected to the said housing.

3. In a device of the character described, followers, a vertical yoke, friction mechanism within the yoke and spring mechanism without the yoke, the friction mechanism comprising a housing, a wedge and friction blocks operating in said housing, and the spring mechanism having a seat engaging the rear follower and straddling the vertical yoke, said spring mechanism being operatively connected to the said housing.

4. In a device of the character described, a yoke, followers, springs, a saddle and spring bolts, in combination with a housing, wedge and friction blocks within the yoke, the said housing being provided with lateral ears to receive the spring bolts, the said spring bolts being connected to the springs and adapted to draw the springs into compression against the saddle on movement of the friction blocks.

5. In a device of the character described, a vertical yoke, followers, friction mechanism within the yoke and spring mechanism without the yoke, means connecting the friction mechanism and the spring mechanism, and a saddle against which the spring mechanism is compressed by said means, the said saddle being seated against the rear follower and independently of the yoke.

6. In a device of the character described, a vertical yoke, followers, friction mechanism within the yoke and spring mechanism without the yoke, means connecting the friction mechanism and the spring mechanism, and a saddle against which the spring mechanism is compressed by said means, the said saddle being seated against the rear follower and independently of the yoke, the said saddle comprising a transverse plate having forwardly extended legs engaging the rear follower.

7. In a device of the character described, a yoke, followers, friction mechanism within the yoke, spring mechanism without the yoke, a saddle, a spring seat and spring bolts, the spring bolts connecting the friction mechanism with the saddle and spring seat, the spring mechanism being seated between said spring seat and the saddle, the saddle being seated against the rear follower and independently of the yoke, the said spring bolts being adapted to compress

the springs between the saddle and spring seat on movement of the friction mechanism.

8. In a device of the character described, a yoke, followers, friction mechanism within the yoke, spring mechanism without the yoke, a saddle, a spring seat and spring bolts, the spring bolts connecting the friction mechanism with the saddle and spring seat, the spring mechanism being seated between said spring seat and the saddle, the saddle being seated against the rear follower and independently of the yoke, the said spring bolts being adapted to draw the springs forwardly into compression between the saddle and spring seat on movement of the friction mechanism.

9. In a device of the character described, followers, a yoke, friction mechanism within the yoke, springs without the yoke, a saddle and spring seat, the friction mechanism comprising a housing, wedge and friction blocks within the housing, the said housing, saddle and spring seat being each

provided with perforations to receive the spring bolts, the springs being seated between the saddle and the spring seat, the saddle being seated against the rear follower and independently of the yoke, the spring bolts being adapted to forwardly compress the springs on movement of the said housing.

10. In a device of the character described, a yoke, followers, springs without the yoke, a housing, wedge and friction blocks within the yoke, spring bolts, a saddle and spring seat, the saddle being seated against the rear follower, the spring bolts passing through the housing, the rear follower, the saddle and spring seat, said spring bolts being adapted to compress the springs between the saddle and spring seat on movement of the housing.
